(57) CLAIM

The ornamental design for an Eiffel Tower cork holder, as shown and described.

DESCRIPTION

FIG. 1 is a front perspective view of an Eiffel Tower cork holder showing my new design;

FIG. 2 is a side view thereof;

FIG. 3 is a back view thereof; and,

FIG. 4 is an enlarged bottom view thereof.

The broken lines depict portions of the Eiffel Tower cork holder that form no part of the claimed design.
